FOLDED SHIRT AND COLLAR PROTECTOR

Stephen Lighter, Whitefish Bay, Wis.

Application September 8, 1947, Serial No. 772,729

2 Claims. (Cl. 223—83)

1

The present invention relates generally to improvements in the art of protecting folded shirts especially after they have been freshly laundered, and relates more specifically to an improved assemblage for protecting the collars of folded shirts or similar garments against collapse or undesirable crushing and wrinkling.

In my prior Patent No. 2,853,344, granted July 11, 1944, I have shown a protector for the collars of folded shirts or the like, comprising a panel formed for coaction with the front outer portion of the collar band of the shirt beneath the collar lapels, a collar band supporting plate swingably connected at its medial portion to the upper central portion of the panel, and a pair of retainer elements formed integral with and disposed on opposite sides of the medial connection between the panel and the plate, and adapted to engage adjacent portions of the plate to hold the latter within the interior of the collar band when the protector is applied to a shirt. The assemblage of this prior patent functions to provide an upright easel for the neck-band of the collar, having inner and outer strips extending along the adjacent inner and outer surfaces of the neck-band, and designed to protect and to keep the collar erect.

Due to the fact that the front central portion of the outer panel of such a bracing easel is necessarily inclined downwardly away from the collar band at a relatively flat angle while the corresponding portion of the inner plate is disposed substantially upright relative to the plane of the shirt bosom, the support provided by the patented protector is not sufficiently rigid to resist extreme downward impacts and pressure exerted against the top of the assemblage adjacent to the clamping elements. I have, however, discovered that this objectionable feature may be effectively eliminated by causing the medial panel and plate connector to not only clampingly engage the midportion of the inner plate, but to also form the top ridge so as to produce a rigid substantially triangular box frame or more durable easel adapted to withstand very much higher downward pressure than the previous assemblages of this type were adapted to resist.

It is therefore a primary object of my present invention to provide an improved collar protector for folded shirts, which is simple in construction, readily applicable and adapted to effectively resist relatively high pressure and impacts directed against the top edge of the collar.

Another object of this invention is to provide an improved shirt collar protecting assemblage

2

which may be manufactured from relatively light paper stock and at minimum cost, to produce a durable and relatively rigid protector.

A further object of the invention is to provide an improved folded shirt and collar protector which may be conveniently applied to a garment, and which when properly applied will not only effectively protect the shirt collar, but will also maintain the shirt in neatly folded condition without utilizing separate fasteners or extensive envelopes.

Still another object of the present invention is to provide an efficient shirt collar protecting device and folded shirt retainer formed of a unitary blank of cardboard or the like, and which may be readily assembled upon the shirt and its collar while being locked in assembled condition.

An additional object of my invention is to provide various improvements in shirt collar protective units of the type shown and described in my above identified prior patent, whereby the strength and effectiveness of such devices is augmented to a maximum, while the cost of production is reduced to a minimum.

The above and other objects and advantages of the invention will be apparent from the following detailed description.

A clear conception of the various features constituting my present improvements, and of the mode of constructing and of utilizing several typical embodiments of the invention, may be had by referring to the drawings accompanying and forming a part of this specification in which like reference characters designate the same or similar parts in the various views.

Fig. 1 is a plan view of a shirt embracing band type of the improved shirt and collar protector, prior to but ready for application to a folded shirt;

Fig. 2 is a plan view of a typical freshly laundered and folded shirt, showing a fragment of one of the protectors of the type depicted in Fig. 1, superimposed upon the shirt preparatory to final application and assembly of the blank;

Fig. 3 is a perspective view of the finally assembled shirt and protector of Fig. 2;

Fig. 4 is a fragmentary outside view of the improved shirt embracing band retainer or lock;

Fig. 5 is a similar fragmentary inside view of my improved shirt embracing band retainer or lock;

Fig. 6 is a plan view of a modified collar protector of the non-shirt-embracing variety;

Fig. 7 is another plan view of a freshly laundered and folded shirt, showing one of the modi-

fied protectors of Fig. 6, superimposed thereon preparatory to final assembly of the blank upon the shirt collar;

Fig. 8 is a perspective view of the finally assembled shirt and collar protector of Fig. 7;

Fig. 9 is an enlarged cross-section taken transversely through the front portion of a shirt neck-band with an improved protector of either type applied;

Fig. 10 is a plan view of a further modified collar protector of the non-shirt-embracing variety;

Fig. 11 is a plan view of a shirt having the further modified protector partially applied;

Fig. 12 is a perspective view of the finally assembled shirt and protector of Fig. 11; and

Fig. 13 is an enlarged section similar to that of Fig. 9, taken through the assemblage of Fig. 12.

In spite of the fact that the invention has been shown and described herein as being especially applicable to protectors formed of cardboard and adapted for application to freshly laundered folded men's shirts, it is not my desire or intent to unnecessarily restrict the formation or utility of the improved devices by virtue of this limited disclosure.

Referring particularly to Figs. 1 to 5 inclusive, and Fig. 9 of the drawings, the improved shirt embracing type of collar protector shown therein is adapted for application to a neatly folded shirt 10 having an attached collar consisting of an inner neck embracing band 11 provided with a front button 12, and an outer fold 13 connected to the upper edge of the neck-band 11 and provided with downwardly directed wings or lapels 14 extending toward the bosom of the shirt 10. These shirts when freshly laundered, may be folded about a special folding board 15 such as shown in Fig. 7, but the use of such board is not essential, and the shirt 10 may be either newly fabricated or freshly laundered.

One of the improved shirt embracing protectors is shown in flat blank formation in Fig. 1, and comprises an elongated retainer band 16 having a widened front section 17 and being of sufficient length to extend around and to overlap at the rear of the bosom portion of the shirt 10 below the collar; an outer central panel 18 projecting upwardly from the mid-portion of the front section 17 of the band 16, and having a pair of external neck-band supports 20 formed integral therewith and projecting away from the opposite sides thereof; an elongated internal neck-band supporting plate 21 disposed parallel and adjacent to the panel 18 and supports 20, and being provided with spaced notches 22 near its medial portion; and an approximately triangular platform 23 swingably connecting the central panel 18 and the plate 21, and having thereon upwardly extending spaced clamping elements 24 adapted for coaction with the notches 22.

The protector blank of Fig. 1 is preferably formed of a single unitary sheet of cardboard or the like, and the band 16 is adapted to snugly embrace folded shirts 10 of slightly different widths, one end of this band being provided with a hook portion 25 while the opposite end thereof is of reduced width and has a series of hook receiving slits 26 and a similar series of locking projections 27 cooperable with the hook portion 25 of the opposite band end, as clearly shown in Figs. 1, 4 and 5. As illustrated in Figs. 4 and 5, the hook portion 25 coacts with the slit 26 and projection 27 farthest from the slotted band end, but the hook portion 25 may also be caused to coact with the other slit and projection, and when the band

ends are thus united in either position, the hook portion 25 is locked within the engaged slit 26 by the corresponding projection 27 and cannot be released without tearing or without extreme difficulty and careful handling. The improved structure thus provides an effective and readily united band fastening devoid of separate pins, clips, pasters or other parts such as are normally utilized for connecting such band ends.

The unitary blanks may be produced with the aid of punches and dies, and the heavier lines of the drawing represent slits cut through the blank body, while the lighter lines are merely score lines for facilitating folding of the adjoining parts.

10 The center of the panel 18 which projects upwardly from the front section 17 of the band 16, is foldably connected with its side supports 20 along inclined score lines 29, and each of the supports 20 is provided with a notched lower portion 30 adapted to interlock with an adjacent recessed projection 31 formed on the band section 17 to maintain the panel 18 in elevated position inclined upwardly away from the shirt bosom and toward the neck-band 11, when the protector has 15 been applied to a shirt 10, as indicated in Figs. 3 and 9. Each of the supports 20 is also provided with an elongated wing 32 adapted to extend beneath the upper ridge of the collar and to snugly engage the adjacent outer surface of the neck-band 11; and when the protector is in use, these wings 32 are urged against the neck-band 11 by the notched portions 30 coacting with the band projections 31.

10 The elongated supporting plate 21 which is 35 clampingly engageable with the interior of the collar band 11 is of approximately rectangular formation, and the notches 22 are formed by cutting the clamping elements 24 of the platform 23 out of the plate stock. The narrower end of the 40 triangular platform 23 merges into the narrower end of the panel 18 without intervening scoring, but the opposite wider end of the platform 23 has its mid-portion separated from the plate 21 by a slot 34, while the portions thereof between the 45 ends of the slot 34 and the adjacent elements 24 are unscored, and the surface of the platform 23 within its boundaries is also free from score or fold lines. The slot 34 which is of considerable 50 importance, may be curved slightly in either direction, or it may be rectilinear; and when a protector thus formed is applied to a shirt 10 as in Fig. 3, the clamping elements will automatically 55 firmly engage the adjacent notches 22 of the plate 21 so as to hold this plate in a position substantially perpendicular to the plane of the shirt bosom, while the edge portion of the slot 34 adjoining the platform 23 will be projected across and will rest upon the edge portion of the same slot which adjoins the upper end of the upright plate, as clearly illustrated in Fig. 9.

60 In some instances it may be unnecessary or even undesirable to provide a shirt embracing protector such as shown in Figs. 1 to 5 inclusive, and in such cases the lower band portions of the 65 protectors and the front panel erecting and holding members may be omitted. Such a modified collar protector is shown in Figs. 6 to 9 inclusive, and this protector is similar to the shirt embracing type except that the modified wings 32' thereof are wider and are swingably attached directly to the opposite sides of the central panel 18 along the score lines 29. The central panel 18 is tapered and united with the narrower end of the 70 triangular platform 23, and the opposite wider end of the latter is connected to the plate 21 be- 75

tween the ends of the slot 34 and the adjacent clamping elements 24, while the plate 21 is provided with notches 22 cooperable with the elements 24, as previously described. This modified collar protector may also be formed of a single sheet of cardboard stock or the like, with the aid of punches and dies, and both types of the improved protectors may be applied to folded shirts 10 in a similar manner.

It has also been found that the benefits of the present improvement are obtainable by omitting the slot 34 and by substituting therefor several weakened fold lines, and such a further modification is shown in Figs. 10 to 13 inclusive of the drawings. The modified protector shown in Figs. 10, 11, 12 and 13 is of the same type as that disclosed in Figs. 6 to 9 inclusive, but instead of utilizing a slot 34 and overlap to reinforce the upper ridge portion of the front easel assemblage, I provide a slightly angular or curved transverse score line 34' connecting the ends of the clamping elements 24 nearest the platform 23, and I also provide another score line 35 bisecting the plate 21 and extending perpendicular to the center of the transverse score line 34'. The central panel 18 is tapered and united with the narrower end of the triangular platform 23 as in the previous modification, and a pair of opposite side wings 32' are hingedly secured along score lines 29 to the inclined opposite side edges of the panel 18. This further modified collar protector may likewise be formed of a single sheet of cardboard stock or the like, with the aid of punches and dies, and when the further modified assemblage is applied to a shirt collar, the plate 21 while being folded within the neckband 11 of the collar will bend abruptly along the score lines 34', 35 and will be drawn inwardly toward the collar band as indicated in Fig. 13 to provide a rigid box structure or easel overlying the front button 12 of the collar and having a relatively sharp and stiff top ridge connecting the clamping elements 24.

While the mode of applying these improved protectors to shirts may be apparent from the foregoing description of the construction thereof, a short résumé will be given. The folded shirt 10 either applied to or removed from a folding board 15, should be laid upon a flat support with the collar directed upwardly, whereupon the protector should be initially applied either as in Fig. 2, 7 or 11, with the collar lapels 14 projected through the slits beneath the plate 21 and above the wings 32, 32'. The protector should then be advanced upwardly to cause the side wings to approach the outer surface of the neck-band 11 beneath the external collar fold, thereby tilting the panel 18 as it approaches the collar button 12, to a position approximately as shown in Figs. 9 and 13. The inner neck-band bracing plate 21 should then be bent laterally and deposited within the collar, and while this is being done, the platform 23 will assume an approximately horizontal position as in Figs. 9 and 13, and the clamping elements 24 thereof will automatically engage the adjacent notches 22 of the plate 21, and the edge of the platform adjoining the slot 34 or score line 34' will coact with the edge of the plate 21 adjoining the top of the easel to provide a stiff top ridge. A box structure of considerable strength and adapted to resist extreme downward pressure, is thus provided at the front of the collar, while the wings 32, 32' and the plate 21 are firmly positioned near the opposite outer and inner surfaces of the collar neck-band 11.

If the collar protector thus applied is of the

type shown in Figs. 6 to 9 inclusive, the attachment thereof to the shirt 10 will have been performed. However, if the protector is of the shirt embracing type shown in Figs. 1 to 5 inclusive, the application thereof to the shirt 10 must be completed by folding the panel 16 at the opposite sides of the panel section 17 along the score lines nearest to the opposite sides of the folded shirt 10, and by thereafter interlocking the hook portion 25 with the proper slit 26 and projection 27 so as to insure snug embracement of the shirt within the band 16. This final attachment of the band 16 may obviously be effected without the aid of separate fasteners, and the interlock afforded by the improved elements is so effective that the band 16 must ordinarily be torn in order to effect subsequent removal of the collar protector.

From the foregoing detailed description of several embodiments of the present improved protectors, it will be apparent that the invention provides an improved shirt and collar protecting device which is extremely durable and strong, even if manufactured from relatively thin and inexpensive stock. The stiff easel or box structure provided by the panel 18, plate 21 and platform 23 at the front of the collar, is adapted to resist considerable pressure and impact without danger of collapsing, and the transverse rigid top ridge of this box structure not only provides for such pressure and impact resistance, but also enhances the clamping action tending to press the wings 32, 32' against the outer side surface of the neck-band 11. The long wings 32, 32' forming integral parts of the panel 18, also enhance the support for the collar ridge, and the improved band fastening assemblage effectively confines the shirt against unfolding and prevents the protector from loosening due to rough handling. The improved protectors can be quickly and readily applied to the folded shirts either while mounted on folding boards 15 or when these boards are omitted, and they may also be manufactured from inexpensive stock and with minimum waste of material. The present improved devices have proven highly satisfactory and successful in actual use, and present an attractive and highly aesthetic appearance when applied to neatly folded clean shirts 10.

It should be understood that it is not desired to limit this invention to the exact details of construction or to the precise mode of use, herein shown and described, for various modifications within the scope of the appended claims may occur to persons skilled in the art; and it is also contemplated that specific descriptive terms used herein be given the broadest possible interpretation consistent with the disclosure.

I claim:

1. In a collar protector for folded shirts, a panel formed for coaction with the outer forward portion of the neck-band of a folded shirt beneath the outer collar and collar lapels, a neck-band clamping plate swingably associated at its medial portion with the medial portion of said panel, and a platform swingably uniting said medial panel and plate portions and having its opposite sides provided with clamping elements engageable with notches in adjacent parts of the plate, said platform being separated at its mid-portion from the adjacent portion of said plate by a slit terminating short of the clamping elements and which provides a weakened fold line forming a stiff top ridge when the protector is applied to a collar.

2. A collar protector as per claim 1, characterized thereby, that the slit is curved so as to cause the upper mid-portion of the platform to project over and beyond the upper end of the mid-portion of the plate at the stiffening ridge in the applied assemblage. 5 STEPHEN LIGHTER.
